United States Patent Office

Des. 191,958
Patented Dec. 19, 1961

191,958

STRINGED MUSICAL INSTRUMENT

Weldon D. Hopper, Rte. 1, Lenoir City, Tenn.

Filed Sept. 2, 1960, Ser. No. 61,996

Term of patent 7 years

(Cl. D56—1)

FIG. 1.

FIG. 2.

FIG. 3.

FIG. 4.

FIG. 5.

FIGURE 1 is a plan view of a stringed musical instrument, showing my new design,

FIGURE 2 is a view from one side,

FIGURE 3 is an enlarged view taken on line 3—3 of FIGURE 1,

FIGURE 4 is a front perspective view of the stringed musical instrument, and

FIGURE 5 is a back perspective view of the stringed musical instrument.

I claim:

The ornamental design for a stringed musical instrument, as shown.
